United States Patent Office

Des. 218,694

Patented Sept. 15, 1970

218,694

WHIRLING AMUSEMENT DEVICE

Julius D. Becker, 21217 De La Guerra,
Woodland Hills, Calif. 91346

Filed Aug. 8, 1969, Ser. No. 18,595

Term of patent 14 years

Int. Cl. D21—02

U.S. Cl. D34—15

FIG. 1 is a front upper perspective view of a whirling amusement device embodying my new design;

FIG. 2 is a side upper perspective view of the device shown in FIG. 1 with the position of its several elements varied.

I claim:

The ornamental design for a whirling amusement device, substantially as shown.
